Primary Examiner—Prashakar G. Deshmukh[57] **CLAIM**

The ornamental design for an air ball game, as shown and described.

DESCRIPTION

FIG. 1 is a perspective view of an air ball game showing my new design;

FIG. 2 is a sectional top plan view thereof; taken along line 2—2 of FIG. 1; and,

FIG. 3 is a sectional elevational view thereof; taken along line 3—3 of FIG. 2.

The broken line showing of ball is for illustrative purpose only and forms no part of the claim.
